COMBINED SEATING AND TABLE UNIT

E Burton Benjamin, Highland Park, Ill., assignor to Sico Incorporated, Minneapolis, Minn., a corporation of Minnesota

Filed May 29, 1967, Ser. No. 7,298

Term of patent 14 years

(Cl. D33—14)

FIG. 1

I claim:

The ornamental design for a combined seating and table unit, as shown and described.
